(57) CLAIM
The ornamental design for a bidet bath mat, as shown and described.

DESCRIPTION

FIG. 1 is an isometric perspective view of my new design for a bidet bath mat;
FIG. 2 is a top plan view of the bidet bath mat;
FIG. 3 is a side elevation of the bidet bath mat;
FIG. 4 is a front elevation of the bidet bath mat; and,
FIG. 5 is a rear elevation of the bidet bath mat.
The broken lines depict environment only and form no part of the claimed design.
